CORRUGATING DIE

Frank P. Bucklein, Los Angeles, Calif., assignor
to Lockheed Aircraft Corporation, Burbank,
Calif.

Application August 27, 1940, Serial No. 354,343

7 Claims. (Cl. 153—76)

This invention relates to improved forming dies for use on simple or single acting power presses such as for example the press brakes used for sheet metal. To this end I have provided a compound, progressive die set to develop the final shape desired in the material being worked upon.

The die set chosen for illustrative purposes is adapted to form a series of non-sinusoidal corrugations in sheet material, the finished material being used as reinforcement beneath the stressed skin covering of airplane wings. In forming such reinforcing material the blank sheet has heretofore been supplied with locating holes or notches fitting over pins on a mandrel, over which a properly formed member is forced to produce the desired shape. In so producing corrugations the locating holes or notches are a source of trouble and delay, and the inherent springback of high strength material has also been a problem, since bending sheet material, without stretching or drawing beyond its yield point, results in unpredictable springback, which varies with the thickness, temper and elasticity of the material. In order to accurately form the corrugations without appreciable stretch, and consequent thinning of the material, I provide a multiple station die set wherein an initial overbend is produced in the material by a semi-folding operation; as distinguished from a drawing operation; in order to allow for subsequent springback upon release from the die, and subsequently utilize a spring pressed plunger to act as a hold-down while another corrugation is being formed by the semi-folding operation.

It is accordingly an object of this invention to provide an improved die for sequentially forming a series of corrugations in sheet material, it being evident that while such corrugations will normally be made parallel to each other, in airplane wing construction it may be advantageous to taper the corrugations and/or slightly converge them for use in wings of tapered profile.

It is a further object of this invention to provide an improved die for use on simple presses or brakes that will accurately and reproducibly form the desired profile without stretching and thinning the material as a result of drawing operations.

Other and further important objects of this invention will be apparent from the disclosures in the specification and the accompanying drawings.

This invention in its preferred form is illustrated in the drawings and hereinafter more fully described.

In the drawings:

Figure I is a fragmentary perspective view of a die set embodying the features of this invention, the length of the dies being limited only by the size of the press or brake with which it is to be used.

Figure II is a fragmentary longitudinal section on the line II—II of Figure I showing the supporting springs and guide pins.

Figure III is a section of the lines III—III of Figure II, in the plane of one of the spring locations.

Figures IV to VII, inclusive, correspond to the line IV—IV in Figure II, and show successive stages in the operation of the dies.

As shown:

The dies of this invention are intended to be used in conventional single acting power presses or sheet metal press brakes, so that to simplify the disclosure no further reference will be made to the press or brake. A lower or female die is built up on a base block 10 having a locating key 11 for aligning it in the press bed; and a cooperating male die has a base block 12 with a hooked key 13 for fastening the same to the movable head or ram of the press.

Since the die, as disclosed, performs two successive operations in forming a single corrugation 14 in a sheet metal blank 15 it will be convenient to describe the separate set-ups for the two steps. To this end, the initial forming mechanism will be first described. The female base block 10 yieldingly supports a die block 16 by means of springs 17, guide pins 18 serving to limit the movement of the block 16. The block 16 is provided with pivots 19 for a lever 20 which is swung upwardly by the closing or downward movement of the block 16 relative to the base 10. The block 16 carries a suitably shaped member 21 which defines the corner to be produced on the sheet metal blank, and the lever 20 supports a similar member 22 which defines the other corner of the corrugation 14; the upward swing of the lever 20 serving to fold the sheet material about a former 23 which is pivotally suspended from the male base block 12. Both corners 21 and 22 and the former 23 are of less radius than the final shape of the corrugation, and allow for springback. The corner member 22 is supported and backed by adjustable shims 24 which control the degree of overbend given the sheet. Also, removal of the supporting shim will allow an offset for overlapping the edges of adjacent sheets of corrugated material. The former 23 is preferably permitted a slight lateral motion, as indicated by the dotted outline in Figure VI, as it is subject to side pressure from the sheet material during the closing movement of the die, both before and after the lever 20 is shifted to fold the material into the position of Figure VII. This also helps to feed the sheet material into the desired shape, rather than to stretch it during the forming operation. When the dies are fully closed, with the lever 20 forced upward, the corner member 22 on the lever forces the sheet material at an angle against a land on the upper or male die. It will be noted that

the movable side wall formed by the lever 20 and the corner member 22 serves to wrap the sheet material about the plunger, bending it through more than a half circle, as indicated in Figure VII. The extent of overbending required may vary with different materials and tempers but is so proportioned that the natural spring-back or opening movement will result in the desired final form.

The hold-down mechanism comprises a plunger 26 formed to cooperate with a complementary channel 27 in the female die 16, the plunger being carried by a plate 28 movable relative to the male base block and backed by springs 29, which springs are of less number and strength than the springs in the lower die so that the plunger 26 will be seated and compressing the previously formed corrugation before the female die is compressed. The plunger 26 is removable in case it is desired to manually control the positioning of the material to produce parallel or converging spacing in the material between or adjacent one or more corrugations, in which case the material would be fed from the right. At the same time as the plunger is seated in the female die 16, the plate 28 bears against lands 30 on either side of the channel 27 so that the plate and plunger serve as hold-downs while the first described parts of the dies are forming another corrugation. The action is a clamping one, as distinguished from a drawing operation wherein the material feeds under the hold-down. The plate 28 and plunger 26 have guide pins 31 and 32 slideable in suitable recesses in the male base block 12, the guide pins 32 having heads limiting the stroke of the plate and plunger.

Figures IV to VII inclusive illustrate successive stages in the operation of the die, Figure IV illustrating the initial position with a pre-formed corrugation 14 in the sheet metal blank 15 positioned in the channel 27 to be engaged by the plunger 26 as indicated in Figure V, with the plate 28 pressing the material against the lands 30 on either side of the channel. During continued downward movement of the upper or male die the springs 29 back of the plate 28 are compressed and serve to hold the sheet material while the former 23 bends the material over the corner piece 21. This bending operation produces reversible side thrust on the former while the sheet is being deformed sufficiently to wrap about the form. During this operation the material feeds over the corner 22 until the dies bottom and force the lever 20 upwardly and inwardly to appreciably overbend the material as indicated in Figure VII.

While the die set chosen for illustrative purposes is particularly adapted to form corrugated reinforcing sheets for aircraft purposes, it is evident that my invention is adapted to a wide field of usefulness, particularly in handling impressions in materials that are ordinarily hard to handle in bending operations where it is not desired to stretch the material.

Having thus described my invention and the present preferred embodiments thereof, I desire to emphasize the fact that many modifications may be resorted to in a manner limited only by a just interpretation of the following claims.

I claim:

1. In a corrugating mechanism of the class described, a base block and an associated female die, a bending member pivoted to said female die and having an outwardly extending portion, and an arcuate upwardly extending portion, said

first named portion being engaged with the base block to provide a fulcrum contact, an opposed base block and an associated male die, means to yieldably support said dies on the blocks, a second bending member pivotally supported on said opposed base block in positions to cooperate respectively with the female die and the first named bending member, whereby the male die will engage and move the female die towards its base block and simultaneously cause the female bending member to rotate around its fulcrum contact towards the female die, to engage a work piece.

2. In a mechanism as set forth in claim 1, wherein the yieldable means that support the dies on the respective base blocks comprise springs acting to force each die away from its respective base block.

3. In a mechanism as set forth in claim 1, wherein the base block that supports the bending member is formed to provide a land portion adjacent the bending member, said land portion being operative to engage and bend the material worked on adjacent the bending member.

4. In a mechanism as set forth in claim 1, wherein the terminal free end of the second named bending member is provided with an adjustable tip portion and means for adjusting said tip portion relative to the body portion of the said bending member to control the degree of bend made in a sheet worked on.

5. In a corrugating mechanism of the class described, in combination, a pair of base blocks, male and female forming members supported respectively on said base blocks, cushioning means associated with each block and being yieldable for movement of each forming member towards its respective base block, a bending member pivotally supported on the block which carries the male forming member, a second bending member fulcrumed on the female forming member and extended to contact the adjacent base block, and means on the supporting base block to engage the second named bending member to move the latter member towards the female forming member in response to relative movement of said last named member on its base block to form a corrugation in the work piece.

6. In a mechanism of the class described in combination, a base block, a female holding die supported on said base block and being yieldably held spaced therefrom by cushion spring means, a female bending die member pivoted at one end to the female holding die and having a portion thereof spaced from the pivoted end of said member in continuous contact with the base block whereby movement of the female holding die and the pivoted end of the die member relative to the base block will cause the die member to swing towards the female holding die, a second base block, a male holding die and a male bending die carried by said second base block and positioned thereon to respectively engage the female holding die and the female bending die.

7. In a device as set forth in claim 6, spring means positioned between the male holding die and its supporting base block, said spring means being weaker than the spring means between the female die member and its supporting block whereby, when the male holding die is moved to engage a work piece between the female holding die and the male holding die, said male holding die will be moved adjacent its supporting block prior to any movement of the female holding die.

FRANK P. BUCKLEIN
